UNITED STATES PATENT OFFICE.

LYDIA LAMPERT, OF CHICAGO, ILLINOIS.

WIRE TIGHTENER.

Application filed June 6, 1921. Serial No. 475,339.

To all whom it may concern:

Be it known that I, LYDIA LAMPERT, a citizen of the United States of America, and a resident of Chicago, county of Cook, and 5 State of Illinois, have invented certain new and useful Improvements in Wire Tighteners, of which the following is a specification.

The main objects of this invention are to provide an improved form of wire tightening device for use in drawing up binding wires on various kinds of objects; to provide an improved arrangement of means for gripping the wires so as to insure the retention of the tightener in place on the object without the use of auxiliary means; to provide an improved arrangement of means for permitting the connection of a tool for actuating said tightener; to provide a tightener which is extremely simple and inexpensive to manufacture, and easy and effective in operation; and to provide a device embodying these characteristics which is especially adapted for use with wires on concrete mold work.

An illustrative embodiment of this invention is shown in the accompanying drawings, in which—

Fig. 1 is a perspective view of a section of a concrete mold showing a wire tightener constructed in accordance with this invention arranged in place thereon.

Fig. 2 is an enlarged perspective view of a wire tightener constructed in accordance with this invention.

Fig. 3 is an enlarged side elevation of the wire tightener showing the connection of the wire thereto and its peculiar relationship by which the tightener is retained in place on the form without the use of auxiliary means.

A wire tightener constructed in accordance with this invention involves an oblong block of polygonal cross-section arranged to have wires secured at the ends thereof so that the wires are disposed perpendicularly to the support against which the block bears and between the edges of the face of the block which abuts against the support. Suitable means are also provided for the connection of a tool for rotating the block.

In the specific form of tightener herein illustrated, the block 1 is of rectangular cross-section, upon the ends of which are arranged pairs of lugs 2. The pairs of lugs 55 2 are spaced apart so as to provide slots 3 and permit the twisting of a wire 4 around

said lugs in some such manner as indicated in Fig. 3.

The faces of the block 1 are provided with recesses 5 which tends to lighten the device 60 and also increase the gripping action of the block to the support against which it bears. Elongated slots 6 formed in the recessed portions of the faces of the block provide for the insertion of a tool by which the 65 block may be revolved.

The tightener herein described and illustrated is adapted to be used substantially in the following manner: The block 1 is placed up against the face 7 of a support 8, which in the drawings is a post forming a part of a concrete mold. The protruding ends 9 of the wire 4 are arranged around the pairs of lugs 2 and through the slot 3 so as to insure a temporary gripping of the wires 75 to the block. The block is then turned by hand a quarter turn or more, depending upon how slack the wires 4 are, until the block bears fairly snugly against the face 7 of the support 8. A suitable tool, preferably in the form of a flat bar, is inserted into the slot 6 and the block turned. The temporary fulcrum of the block is one of the longitudinal edges which shifts upwardly as the block completes its turn and 80 allows another face thereof to be set against the face of the support 8. The block is turned a quarter or half turn, (more if necessary), depending upon the slackness of the wire 4 and the amount of yield that there is 85 in the form or other object around which the wire extends.

The wire connected in this manner to the block securely holds the block in place upon the support without the use of auxiliary 95 means for the reason that the wire 4 is disposed perpendicularly to the face 7 of the support 8 between the edges 10 and 11 of the face which abuts against said support.

Although but one specific embodiment of 100 this invention has been herein shown and described, it will be understood that numerous details of the construction shown may be altered or omitted without departing from the spirit of this invention as defined 105 by the following claims.

I claim:

1. A wire tightener comprising an oblong block of polygonal cross section adapted to have one face rest flat against a support, a 110 part of said block being of materially reduced cross section compared with the main

portion of said block so that a wire wrapped around said reduced part and extending perpendicular to said one block face will be disposed a substantial distance inwardly 5 from the adjacent longitudinal edge of said one block face, whereby the block will hold the wire under tension without a locking device, and means on said block adapted to permit the connection of a tool to said 10 block for revolving the same.

2. A wire tightener, comprising an oblong block of polygonal cross-section adapted to bear against the face of a support, and having slots formed in the ends adapted to grip 15 a wire so that when the block is turned to take up the slack in the wire said wire will be disposed perpendicularly to the face of the support intermediate the edges of the face of said block which abuts against the 20 support and means adapted to permit the connection of a tool to said block for revolving the same.

3. A wire tightener, comprising an oblong block of polygonal cross-section adapted to 25 bear against the face of a support, and having slots formed in the ends adapted to grip a wire so that when the block is turned to take up the slack in the wire said wire will be disposed perpendicularly to the face 30 of the support intermediate the edges of the face of said block which abuts against the support, said block having other slots arranged therein intermediate the ends and adapted to permit the connection of a tool 35 for revolving said block.

4. A wire tightener, comprising an oblong block of rectangular cross-section adapted to bear against the face of a support, a pair of lugs at each end of said block, said lugs being spaced apart so as to form a slot be- 40

tween them and being adapted to have a wire connected thereto so as to be disposed perpendicularly to the support intermediate the edges of the face of said block which abuts against the support, and means adapted to permit the connection of a tool to said block for revolving the same. 45

5. A wire tightener, comprising an oblong block of rectangular cross-section adapted to bear against the face of a support, a pair 50 of lugs at each end of said block, said lugs being spaced apart so as to form a slot between them and being adapted to have a wire connected thereto so as to be disposed perpendicularly to the support intermediate 55 the edges of the face of said block which abuts against the support, said block having slots formed in the several faces thereof intermediate the ends and adapted to permit the insertion of a tool for revolving said 60 block.

6. A wire tightener, comprising an oblong block of rectangular cross-section adapted to bear against the face of a support, said block having the faces thereof recessed longitudinally from end to end, a pair of lugs formed on each end of said block, the lugs of each pair being spaced apart so as to form a slot therebetween and being adapted to have a wire secured thereto so as to be disposed 65 perpendicularly to the face of the support intermediate the edges of the face of said block which abuts against the support, said block also having slots formed in the faces thereof intermediate the ends and adapted 70 to have a tool connected thereto for making the same. 75

Signed at Chicago this 3d day of June 1921.

LYDIA LAMPERT.
